UNITED STATES PATENT OFFICE

104,754

DESIGN FOR AN AUTOMOBILE HEATER

Philmore F. Sperry, Chicago, Ill., assignor to
Excel Auto Radiator Company, Chicago, Ill.,
a corporation of Delaware

Application March 22, 1937, Serial No. 68,324

Term of patent 3½ years

To all whom it may concern:

Be it known that I, Philmore F. Sperry, a citizen of the United States, residing at Chicago, in the county of Cook and State of Illinois, have invented a new, original, and ornamental Design for Automobile Heaters, of which the following is a specification, reference being had to the accompanying drawing, forming part thereof.

Fig. 1 is a front elevation of an automobile heater showing my new design, and

Fig. 2 is a plan view of the heater.

I claim:

The ornamental design for an automobile heater as shown.

PHILMORE F. SPERRY.
